REPEATING FUSE CONSTRUCTION

William O. Schultz, South Milwaukee, and Alwin G. Steinmayer, Milwaukee, Wis., assignors to Line Material Company, South Milwaukee, Wis., a corporation of Delaware

Application July 18, 1935, Serial No. 32,006

20 Claims. (Cl. 200—126)

This invention relates to a repeating fuse construction and is particularly directed to a construction in which a device is provided which closes the circuit after the blowing of a fuse and connects a fresh or reserve fuse in the circuit, such device being capable of repeating as many times as the device is designed for.

The advantage of this automatic repeating fuse construction is that the device lends itself to transmission service and customer's substation service. Frequently in these services short-circuits occur due to any one of many causes, such as a tree falling across a pair of lines, a pair of lines being whipped together by a wind, a flash-over, a temporary ground, or the branch of a tree which in a violent wind may be blown against the line. Under these and similar conditions it frequently happens that the trouble is only temporary and that it either ceases of itself or the fault is burned out almost immediately.

This invention is designed to provide a device which will take care of conditions such as outlined above, which will electrically disconnect the blown fuse from the line, and after a predetermined brief interval immediately connect a reserve or fresh fuse in the line, such device providing for the successive operation of as many fuses as the device is equipped to handle, and to provide a device of this type in which the time delay interval is obtained by an automatic time delay device.

This invention provides for the renewal of a blown fuse without interrupting the service, and objects of this invention are to provide a construction which permits the ready removal and refusing of the blown fuse, which permits the ready restoring of such refused fuse, and the automatic disconnecting of the next adjacent auxiliary or reserve fuse without at any time interrupting the circuit during this restoring operation.

Further objects of this invention are to provide a housed type of drop-out repeating fuse construction in which as many housed types of fuses may be related as required for the given number of repetitions elected, and in which although each fuse is housed, nevertheless it drops or moves out of position after blowing and projects from its particular housing, thus giving a visual indication of the particular fuse that has blown.

Further objects are to provide a repeating fuse construction in which each fuse assembly is mechanically held in place prior to blowing so that no cocking or setting of a fuse into operative position has to take place, and in which the fuse

assembly may include both the fuse tube and the door of the housing.

Further objects are to provide a novel type of housed repeating fuse construction in which automatic timing means is provided which may be adjusted for the particular time interval desired before the circuit is connected through the next fuse, in which the adjustment in timing may be varied, in which the closing motion of the connecting switch is retarded during the initial portion of the closing, and in which the final closing stroke of the connecting switch is quick so that a quick closing of the switch takes place, preferably arc fingers being provided to protect the contacts.

Further objects are to provide a housed type of drop-out repeating fuse which may take any one of several forms, in one form each fuse carrying the door of its housing and in another form the fuse dropping out after blowing while the door remains closed. However, the invention contemplates a construction such that the door may be pulled open if desired to open the circuit through any given fuse in all forms of the invention, and the mechanism automatically reconnects the next adjacent fuse in circuit whether the preceding fuse has automatically dropped out or has been manually pulled out, and in which after a fuse has blown, it may be readily refused and may be readily put back into circuit without interrupting the service, the renewed fuse unit making good electrical contact prior to the opening of the circuit for the next adjacent fuse.

Further objects are to provide a drop-out fuse construction of the repeating fuse type in which the several fuse units are so made that positive contact is maintained between the stationary contacts of the housing and the contacts carried by the fuse tube which ultimately moves away from the stationary contacts, such positive contact, however, being maintained for an appreciable interval of time to insure complete clearing of the fuse tube prior to breaking of the contact between either contact of the fuse tube and the corresponding stationary contact carried by the housing, thus guarding against any possibility of arc-ing over, the invention in greater detail contemplating the use of an arc finger or arc fingers, certain of which are movable with respect to the fuse tubes so that the particular arc finger carried by or cooperating with the movable fuse tube will insure maintenance of contact with the stationary contact for the desired length of time hereinbefore mentioned.

Further objects are to provide a drop-out re-

peating fuse construction in which the connecting switch for connecting the next adjacent fuse unit remains housed although the door and the fuse tube of the blown unit drop to open position, such door and fuse tube first rocking outwardly adjacent their lower end and thereafter rocking bodily downwardly to full open position, thus completely separating the fuse unit from the stationary contacts, the hinge construction for the fuse assembly being electrically dead after the fuse assembly has dropped to open position.

Embodiments of the invention are shown in the accompanying drawings, in which:

Figure 1 is a vertical sectional view through the device with parts broken away showing one of the fuse units in operative position in full lines and showing in dotted lines the successive positions taken by the fuse tube assembly as it moves to open position.

Figure 2 is a fragmentary view, partly in section, showing details of the time delay mechanism.

Figure 3 is a fragmentary view showing a group of fuse units in the relative positions they occupy.

Figure 4 is a view similar to Figure 3 showing how the fuse units may be carried in a unitary or integral housing.

Figure 5 is a view, partly in section, showing a further form of the invention and showing one of the fuse units in full lines in operative position and showing the fuse unit in an early stage of its motion as it is travelling towards inoperative position after blowing of the fuse.

Figure 6 is a bottom view of the structure shown in Figure 5.

Figure 7 is a fragmentary detail on the line 1—1 of Figure 5 showing the manner of holding the door temporarily closed.

Figure 8 is a detail of the bottom of the structure shown in Figure 5.

Figure 9 is a side view, partly in section, showing a modified form and indicating how the spring pressed contact finger can be applied to a fuse of the type shown in Figure 1.

Referring to the drawings, particularly Figures 1 and 3, it will be seen that the device comprises a plurality of housings 1 which are provided with doors 2 equipped with manipulating members or eyelets 3 and with removable upper covers 4 for the automatic connecting switch and timing mechanism hereinafter described, such covers being removably held in place in any suitable manner as by means of the screws 5. If desired, the doors 2 may be hinged, as will hereinafter appear, upon a supporting link 6.

The door is provided with a pair of arms 7 between which the lower collar 8 carried rigidly by the fuse tube 9 is pivoted, as indicated at 10. The lever 6 is bifurcated adjacent its upper end and is pivoted upon the pin 10 so that the door is pivotally supported by the contact lever 6.

The lower end of the contact lever is provided with a pair of trunnions 11 which are received within the hook like hinge member 12, such hinge member being provided in duplicates and having inwardly projecting stops 13 against which the supporting contact lever 6 strikes when the fuse assembly is in its lowest position, as shown in the lowest dotted line position shown in Figure 1.

The fuse tube is held in approximately the position shown in Figure 1 with reference to the door as a spring 14 is carried by the door and bears against the lower end of the fuse tube, thus forcing the fuse tube towards motion in a clockwise direction, but allowing a limited motion to occur

between the fuse tube and the door when the door is pulled outwardly, as will hereinafter appear.

The upper end of the fuse tube is provided with an upper contact 15 provided with a cap 16 in the usual manner for clamping the fuse link in place, the lower portion of the fuse link being indicated by the reference character 17 in Figure 1 and extending through the lower end of the expulsion fuse and over the lower portion of the lever 6 and being clamped in place by the thumb nut 18. 10

The housing or body portion 1 is provided with an upper terminal member 19 and with a lower terminal member 20. The member 20 is provided with a brush or other form of contact 21 which bears against the contact lever or supporting lever 15 6 when the fuse is in its operative position, as shown in full lines in Figure 1. This brush contact 21 also follows the lever 6 outwardly a material distance as the fuse starts on its outward motion after rupture of the fuse link and thus insures clearing of the fuse tube prior to breaking of the contact. However, the lever 6 itself may be provided with a spring urged contact finger, as will appear as the description proceeds.

The contact 15 at the upper end of the fuse tube is provided with outwardly projecting pins 22 which normally are positioned behind the slanting cam faces 23 of a pair of spring arms 24 carried by the upper terminal member 19. The door is provided with a pair of bulged or cam-shaped spreading members 25 which are located inside of the spring fingers 24 and when the door is pulled outwardly, these members 25 spread the spring fingers 24 sufficiently to allow the pins 22 to pass, thus permitting the manual opening of 35 the fuse tube assembly, though this specific arrangement forms no portion of the present invention, and is more fully described in the co-pending application of William O. Schultz for Fuses, Serial No. 650,815, filed January 9, 1933. 40

The upper terminal member is provided with a bracket 26 which has outwardly projecting rigid arms 27 between which the timing mechanism and connecting switch are carried.

The connecting switch includes an upper stationary contact 28 which is normally free from engagement with a movable switch arm 29 which latter may take the form of a brush contact and may also have an arc finger 30. This connecting switch connects the upper terminal 19 with 45 the upper contact 28, the latter being connected by means of the conductor 31, see Figure 3, with the upper terminal 19 of a succeeding fuse, the lower terminal members 20 being permanently connected by the conductors 31', see Figure 3. 51

The switch contact 29 is carried by a lever 32, see Figure 1, which is spring pressed towards switch closed position by means of the spring 33. It is preferable to provide a flexible leader 34 which directly connects the switch arm with the 60 terminal 19. If desired, this leader 34 may continue to the upper contact 35 of the housing, which latter is also in the form of a rocking lever pivoted as indicated at 36 and spring pressed downwardly into firm electrical contact with the 65 upper contact of the fuse tube.

The contact lever 35 carries a pair of slotted links 37 within whose slots pins 38 carried by the lever 32 are positioned.

It is to be noted particularly that when the 70 fuse assembly is in its closed position, that the links 37 hold the lever 32 and consequently the switch arm 29 in open position. However, when the fuse blows, the downward pressure of the lever 35 assists in the initial opening movement of the 75

5 fuse assembly, but the contact 35 follows the upper contact of the fuse tube downwardly a material distance and thus prevents breaking of the contact at this point until the fuse tube has had ample time to clear itself.

10 The opening movement of the fuse tube, it is believed, will be apparent from the dotted line indications in Figure 1. However, it will be seen that when the fuse link 17 is ruptured, that the lower portion of the fuse tube assembly rocks outwardly, as shown in the upper dotted line position in Figure 1, and that the pins 22 thus slide downwardly and finally clear the cam faces 23. The fuse tube assembly now rocks downwardly to its final position, as shown in the lowest dotted line position in Figure 1, until the link 6 is arrested by the stops 13.

15 It is clear that when the fuse tube moves to open position, that the lever 35 releases the switch arm 29 through the mechanism hereinbefore described. The closing of the switch is retarded by means of the time delay mechanism which may consist of a pair of pivoted metal bellows 39 and 40, the bellows preferably containing oil or 20 other suitable liquid and the bellows 40 constituting merely a storage compartment for receiving the liquid discharged from the bellows 39, as will appear later.

25 The bellows 39 and 40 are joined to a head 41 which is pivoted as indicated at 42 between the arms 27. The movable head 43 of the bellows assembly is pivotally carried between the arms of a cam lever 44, such cam lever itself being pivoted as indicated at 45. This cam lever is 30 provided with a transverse curved or cam-shaped face 46, see particularly Figure 2, upon which a roller 47 carried between the extension arms 48 travels. These extension arms 48 are bolted to the switch arm 29 and the lever 32, as is seen from 35 Figure 1.

40 It is apparent, therefore, that upon release of the closing switch, that the spring 33 urges such switch towards closed position and that the closing motion is retarded due to the fact that the bellows 39 is being compressed and is discharging liquid through the small orifice 49, see Figure 2, into the storage bellows 40. The shape of the cam member or face 46 is such that slow closing motion occurs throughout the major portion of 45 the closing stroke of the switch, but that on the final closing stroke, the switch suddenly closes with a quick motion. This is accomplished by the peculiar shaping of the surface 46.

45 If desired, an adjusting screw 50, see Figure 2, may be provided to limit the initial opening motion of the bellows 49, which opening motion is produced by means of a spring 51 carried within the bellows 39. Thus a quicker closing of the switch will occur if this screw 50 is set inwardly as the bellows is already held partly compressed. The screw 50, of course, may be locked in place by means of a lock nut, as shown in Figure 2.

50 It is to be noted that the timing mechanism and the connecting switch in each fuse unit is 55 separately housed and access may be had thereto by removal of the caps or closure members 4, see Figures 1 and 3. These switches are, therefore, protected from the weather even when the fuse assembly drops to open position.

55 Further it will be seen that when a fuse blows, ample time is allowed for the clearing of the fuse tube, although the blowing of the fuse may occur under small overload conditions where a high pressure does not suddenly build up in the fuse tube. Additionally, it is to be noted that the con-

tact lever or supporting lever 6 withdraws any remaining portion of the fuse link when the fuse tube assembly rocks to open position. Also it is to be noted that there is a very wide spacing of the contacts when the fuse tube assembly has 5 rocked to open position and thus there is no chance of leakage between the stationary contacts of the housing.

10 An additional safety feature resides in the fact that the hinge members 12 are electrically dead 10 after the fuse has blown and are not connected to either contact of the housing either directly or through any intermediate mechanism.

15 In the form of the invention shown in Figures 5, 6, 7 and 8, a construction is illustrated in which 15 the door is not carried by the fuse tube but in which the door remains closed while the fuse tube or fuse assembly drops to open position, and is an improvement over that disclosed in Patent No. 1,949,186 of February 27, 1934, issued to William 20 O. Schultz, for Fuse.

25 In this form of the invention the casing is indicated by the reference character 52, but it is to be distinctly understood that this casing may be made either separate for each unit of the repeating fuse construction, as shown in Figure 3, or all of the casings may be made as one integral unit as indicated for two units in Figure 4, the figure, however, being designed to represent any 30 number of units in which the casings are of integral construction.

35 The casing is provided with a door 53 and with an upper cover 4 for the timing mechanism, such mechanism being similar to that previously described and a portion of which being indicated 35 in Figure 5.

40 The fuse tube 54 is provided with a metal collar 55 adjacent its lower end and with an upper contact including a cap 56 and a rectangular metal member 57 somewhat similar to that described in 40 connection with Figure 1. The fuse tube is open at its lower end and the fuse link 58 extends through such open end, as previously described, and is clamped by means of a thumb nut 59 to the supporting contact lever 60.

45 The contact lever 60 is also shown in Figure 8 and it will be seen that it is pivoted, as indicated at 61, to the ferrule or collar 55 and thus supports the fuse assembly or fuse tube under normal conditions. The lever, however, is held relatively immovable with respect to the fuse tube by the fuse link 58 and thus restrains the fuse tube from 50 rocking outwardly adjacent its lower end and dropping downwardly until the fuse link is severed. This contact lever or supporting lever 60, as may be seen from Figures 5 and 8, is provided 55 with trunnions 62 which project outwardly from opposite sides adjacent the lower ends thereof, such lower ends being provided with ears or, in 60 other words, substantially bifurcated, as is apparent from an examination of Figure 8.

65 These trunnions 62 are pivotally carried by ears 63 formed integrally with the door 53 and project beyond such ears. They are removably seated 65 within hook like supports 64 or lower hinge members which are carried adjacent the lower portion of the casing so that the door and fuse assembly may be lifted out, if so desired, as for example when refusing.

70 The lever 60 is provided with a contact finger 65 which is pivotally mounted upon the pin 66 and positioned within a cut-out portion in the lever 60. It is urged by means of a spring 67 so 75 that its upper arm is pressed into engagement

with the contact 21 of the lower contact, see Figures 5 and 8.

Normally the contact finger is held within the cut-out portion of the lever 60 by the brush contact 21, such brush contact engaging not only the contact finger 65 but the lever 60 as well under normal conditions. The lower portion of the contact finger or contact lever 65 is provided with a bearing part or member 68 which normally presses against the fuse tube 54, as may be seen from Figure 5. The upper contact or portion 57 is provided with outwardly projecting pins 69, see particularly Figure 7, which fit within slots 70 formed in the spring ears or arms 71 carried by the door 53. The arms 71 are provided with outwardly turned portions 72 which fit behind inwardly turned portions 73 of contact fingers or gripping fingers 74 carried by the upper terminal member 19, such fingers terminating in outwardly diverging extensions 75 so that the door may be forced closed, thus spreading the fingers 74 until the portions 72 snap back of the portions 73 and thus temporarily lock the door closed. However, the door may be pulled open to thus withdraw the fuse from circuit manually if so desired, as the portions 72 slant on their outer sides and act as cams to spread the fingers 74 and thus allow the opening of the door.

However, the fuse can drop down without opening the door, as it is apparent from Figures 5 and 7 that the slots 70 open downwardly and when the fuse is released upon blowing of the fuse link 58, the pins 69 move downwardly out of the slots 70, as indicated in Figure 5.

Upon blowing of the fuse link 58, the lever 60 is released and the lower end of the fuse rocks outwardly and then downwardly, the door 53 being sufficiently flared adjacent its lower end to allow the fuse tube to execute its motions and drop outwardly from circuit, the fuse tube after passing from the door rocking downwardly to an approximately vertical position and projecting downwardly from the casing and door.

During the initial outward motion of the fuse tube, as indicated in dot and dash lines in Figure 5, the upper contact finger 35 maintains contact with the upper contact of the fuse tube for a material length of time and the lower contact finger 65 maintains contact with the brush contact 21, thus preventing breaking of the circuit at either the upper or lower contacts until the fuse has had ample time to clear itself. This prevents any possibility of arcing at either the upper or lower contacts.

The timing mechanism is released, as previously described, and connects a successive fuse in circuit after the desired length of time has elapsed.

It is to be distinctly understood that the contact finger 65 may be applied to the construction shown in Figure 1 or the brush contact arrangement, as shown in Figure 1, may alone be relied upon for the form shown in Figure 5. In other words, the parts may be interchanged wherever found most desirable.

Figure 9 shows the manner in which the lower contact finger can be applied to the construction shown in Figure 1. In this figure the fuse tube is indicated by the reference character 76 and is provided with a collar 77 which is hinged as indicated at 78 between the fingers 79 carried by the door. A spring 80 urges the fuse tube towards rocking motion in a clockwise direction, all as described in connection with Figure 1. The contact lever or supporting lever is indicated by the reference

character 81 and supports the fuse tube and door, as previously described in connection with Figure 1. However, this lever is provided with a contact finger 82 which is spring urged outwardly by means of a spring 83 similarly to that described in connection with Figure 8. The contact finger or lever 82 is provided with an extension 84 which bears against the fuse tube under normal conditions while the fuse link 85 is intact, the fuse link 85 being clamped to the lever 81 by means of the thumb nut 86.

This contact finger is identically the same as that described in connection with Figure 8 and serves to maintain a prolonged contact with the lower stationary contact, thus insuring clearing of the fuse prior to opening of the contacts.

In connection with Figure 5 as described in connection with Figure 1, it is to be noted that the lower hinge members are electrically dead after the fuse has blown and dropped to open circuit or inoperative position.

Figures 3 and 4 are intended to indicate that either type of fuse units may be made as separate and distinct members in their individual casings or the structure may be made with an integral casing structure for all of the fuse units, only two having been illustrated in Figures 3 and 4, but, of course, any number may be employed depending on the number of successive operations desired.

Although housed type of fuses have been shown, nevertheless these fuses are of the drop-out type, and, in addition, may be associated with other drop-out type fuses so that a repeating fuse construction is secured. The time interval between the connecting of successive fuse units is predetermined and adjustable for any desired interval.

If desired the invention may be applied to open type drop-out repeating fuses. However, the housed type drop-out fuse is preferred as it may be mounted in an exposed position without damage from rain, sleet or snow. Also the individual protection of the timing mechanism and connecting switch for successive fuses is maintained whether the fuse is of the type in which the door drops open or remains closed after the fuse blows.

It is to be distinctly understood that the succeeding fuses need not necessarily be of the same type or, in fact other types of cut-outs than fuses may be employed if desired, though the preferable construction is, of course, a series of fuses, that is to say, each unit being a fuse in itself.

With reference to the construction shown in Figures 5, 6 and 7, it is apparent that the door need not allow the fuse to drop completely downwardly from the casing, provided the door affords sufficient space for the fuse to drop outwardly to completely open both the upper and lower contacts. Also it is to be noted that it is preferable to use the contact finger carried by the lower lever, as this contact finger not only operates in the manner hereinbefore described, but also serves to withdraw any remaining portion of the fuse link after the fuse has blown.

Although this invention has been described in considerable detail, it is to be understood that such description is intended as illustrative rather than limiting, as the invention may be variously embodied and is to be interpreted as claimed.

We claim:

1. In a repeating fuse construction, the combination of a plurality of fuse units, at least the

first fuse unit comprising a casing having spaced stationary contacts, a fuse tube assembly including a door for said casing and a fuse tube, said fuse tube having an upper and a lower contact 5 and a fuse link within said tube normally forming a connecting member between said upper and lower contacts, the lower contact of said fuse tube including a supporting lever for said fuse tube assembly, said lever being pivoted at one end to said fuse tube assembly and at the other end to said casing, said link normally restraining said lever against motion with reference to said fuse tube assembly, an electric line normally connected through the first of said fuse 10 units, and an automatic switch releasable by the motion of the fuse tube assembly of said first fuse unit for connecting the electric line through a successive fuse unit.

2. In a repeating fuse construction, the combination of a plurality of fuse units, at least the first fuse unit comprising a casing having spaced stationary contacts, a fuse tube assembly including a door for said casing and a fuse tube, said fuse tube having an upper and a lower contact and a fuse link within said tube normally forming a connecting member between said upper and lower contacts, the lower contact of said fuse tube including a supporting lever for said fuse tube assembly, said lever being pivoted at one end to said fuse tube assembly and at the other end to said casing, said link normally restraining said lever against motion with reference to said fuse tube assembly, an electric line normally connected through the first of said fuse units, 30 and a switch biased towards closed position and released by the outward motion of said first fuse tube assembly for connecting the electric line through a successive fuse unit.

3. In a repeating electrical construction, the combination of a plurality of fuse units, the first fuse unit comprising a casing having spaced stationary contacts, a fuse tube assembly including a door for said casing and a fuse tube, said fuse tube having an upper and a lower contact and a fuse link within said tube normally forming a connecting member between said upper and lower contacts, the lower contact of said fuse tube including a supporting lever for said fuse tube assembly, said lever being pivoted at one end to said fuse tube assembly and at the other end to said casing, said link normally restraining said lever against motion with reference to said fuse tube assembly, an electric line normally connected through the first fuse unit, an 50 automatic switch housed within the first fuse unit and biased towards closed position for connecting the electric line through a succeeding fuse unit, said switch being released when the first fuse tube assembly drops to open position, 55 and time delay mechanism for delaying the closing motion of said switch.

4. A repeating electrical construction comprising a plurality of cut-outs including at least a first cut-out and a second cut-out, said first cut-out comprising a housing having a door and a fuse tube constituting jointly a fuse tube assembly, means for guiding said fuse tube assembly for opening the electric circuit through said first cut-out by the mechanical motion of said fuse 60 tube assembly from operative to inoperative position, restraining means including a fuse link within the fuse tube for normally holding the fuse tube assembly in place, and a normally open switch biased towards closed position carried by 65 said first cut-out for establishing connection 70 through said second cut-out upon blowing of said 75

through said second cut-out upon blowing of said first cut-out.

5. A repeating electrical construction comprising a plurality of cut-outs including at least a first cut-out and a second cut-out, said first cut-out comprising a housing having a door and a fuse tube constituting jointly a fuse tube assembly, means for guiding said fuse tube assembly for opening the electric circuit through said first cut-out by the mechanical motion of 10 said fuse tube assembly from operative to inoperative position, restraining means including a fuse link within the fuse tube for normally holding the fuse tube assembly in place, a normally open switch biased towards closed position 15 carried by said first cut-out for establishing connection through said second cut-out upon blowing of said first cut-out, and time delay mechanism for delaying the closing motion of 20 said switch.

6. A repeating electrical construction comprising a plurality of cut-outs including at least a first cut-out and a second cut-out, said first cut-out comprising a housing having a door and a fuse tube constituting jointly a fuse tube assembly, means for guiding said fuse tube assembly for opening the electric circuit through said first cut-out by the mechanical motion of 25 said fuse tube assembly from operative to inoperative position, restraining means including a fuse link within the fuse tube for normally holding the fuse tube assembly in place, a normally open switch biased towards closed position carried by said first cut-out for establishing connection through said second cut-out upon blowing of 30 said first cut-out, and time delay mechanism for delaying the closing motion of said switch, said switch having a slow initial closing motion and a quick final closing motion.

7. A repeating electrical construction comprising a plurality of cut-outs including at least a first cut-out and a second cut-out, said first cut-out comprising a housing having a door and a fuse tube constituting jointly a fuse tube assembly, means for guiding said fuse tube assembly for 40 opening the electric circuit through said first cut-out by the mechanical motion of said fuse tube assembly from operative to inoperative position, restraining means including a fuse link within the fuse tube for normally holding the fuse tube 45 assembly in place, a normally open switch biased towards closed position carried by said first cut-out for establishing connection through said second cut-out upon blowing of said first cut-out, and time delay mechanism for delaying the closing motion of 50 said switch, said switch having a slow initial closing motion and a quick final closing motion, said switch including an arc finger and a main movable switch arm.

8. A repeating electrical construction comprising a plurality of cut-outs including at least a first cut-out and a second cut-out, said first cut-out comprising a housing having a door and a fuse tube constituting jointly a fuse tube assembly, means for guiding said fuse tube assembly for 60 opening the electric circuit through said first cut-out by the mechanical motion of said fuse tube assembly from operative to inoperative position, restraining means including a fuse link within the fuse tube for normally holding the 65 fuse tube assembly in place, a normally open switch biased towards closed position carried by said first cut-out for establishing connection through said second cut-out upon blowing of said 70 fuse tube assembly in place, and a removable cover for said 75

switch, whereby said switch will be covered after said door has swung to open position.

9. A repeating electrical construction comprising a plurality of cut-outs including at least a first 5 cut-out and a second cut-out, said first cut-out comprising a housing having a door and a fuse tube constituting jointly a fuse tube assembly, means for guiding said fuse tube assembly for opening the electric circuit through said first 10 cut-out by the mechanical motion of said fuse tube assembly from operative to inoperative position, restraining means including a fuse link within the fuse tube for normally holding the fuse tube assembly in place, a normally open switch 15 biased towards closed position carried by said first cut-out for establishing connection through said second cut-out upon blowing of said first cut-out, time delay mechanism for delaying the closing motion of said switch, and means for adjusting said time delay mechanism to change the interval of closing of said switch.
10. A repeating electrical construction comprising a first cut-out and a second cut-out, said first cut-out including a housing having a door 20 and a fuse tube carried by said door and constituting a fuse tube assembly, lever mechanism for holding said fuse tube assembly in closed position and movable to allow the fuse tube assembly to rock outwardly to open position, a fuse link in 25 said fuse tube restraining the lever mechanism against movement with respect to said fuse tube assembly, said first cut-out having a switch biased towards closed position for connecting said second cut-out in circuit upon blowing of said first cut-out, time delay mechanism for delaying the closing of said switch, and a downwardly 30 pressed movable member engaging the fuse tube of said first cut-out and electrically connected thereto, said movable member controlling the 35 closing motion of said switch.
11. A repeating electrical construction comprising a first cut-out and a second cut-out, said first cut-out including a housing having a door and a fuse tube carried by said door and constituting a fuse tube assembly, lever mechanism for holding said fuse tube assembly in closed position and movable to allow the fuse tube assembly to rock outwardly to open position, a fuse link in 40 said fuse tube restraining the lever mechanism against movement with respect to said fuse tube assembly, said first cut-out having a switch biased towards closed position for connecting said second cut-out in circuit upon blowing of said first cut-out, time delay mechanism for delaying the closing of said switch, and a downwardly 45 pressed movable member engaging the fuse tube of said first cut-out and electrically connected thereto, said movable member controlling the closing motion of said switch, said movable member being arranged in the path of movement of said fuse tube, whereby when the fuse tube assembly of said first cut-out is rocked to closed position, said movable member will be retracted to thereby open said switch.
12. A repeating electrical construction comprising a first cut-out and a second cut-out, said first cut-out including a housing having a door and a fuse tube, lever mechanism for holding said fuse tube in closed position and movable to allow 50 said fuse tube to rock outwardly to open position, said housing having contacts, a fuse link carried by said fuse tube and normally restraining said lever against motion relatively to said fuse tube, said link normally electrically connecting the 55 contacts of said housing, a contact lever pivotally 60 carried by said first mentioned lever for maintaining contact with one of the contacts of said housing for a material time during the opening motion of said fuse tube, an electric line normally connected through said first cut-out, and switch means controlled by the position of said fuse tube for connecting said electric line through said second cut-out upon blowing of said first cut-out.
13. A repeating electrical construction comprising a first cut-out and a second cut-out, said first cut-out comprising a housing having a door and a fuse tube, means for guiding said fuse tube for opening the electric circuit through said first cut-out by the mechanical motion of said fuse tube from operative to inoperative position, restraining means including a fuse link within the fuse tube for normally holding the fuse tube assembly in place, said housing having contacts normally electrically connected by said fuse link when said fuse tube is in operative position, a contact lever carried adjacent the lower portion of said fuse tube for maintaining contact with one of the contacts of said housing during a portion of the opening motion of said fuse tube, and switch means controlled by the position of said fuse tube for establishing connection through said second cut-out upon blowing of said first cut-out.
14. A repeating electrical construction comprising a first cut-out and a second cut-out, said first cut-out comprising a housing having a door and a fuse tube, means for guiding said fuse tube for opening the electric circuit through said first cut-out by the mechanical motion of said fuse tube from operative to inoperative position, restraining means including a fuse link within the fuse tube for normally holding the fuse tube in place, said housing having spaced contacts, contact fingers located adjacent opposite ends of said fuse tube for maintaining contact between said fuse tube and the contacts of said housing during a portion of the opening motion of said fuse tube, and switch means controlled by the position of said fuse tube for establishing connection through said second cut-out upon blowing of said first cut-out.
15. A repeating electrical construction comprising a first cut-out and a second cut-out, said first cut-out comprising a housing having contacts, a door for said housing, said door and housing providing a downwardly flaring opening in the lower portion of said structure, a fuse assembly having spaced contacts normally engaging the contacts of said housing, mechanism releasably holding said fuse assembly in position, a fuse link forming a portion of said fuse assembly and normally holding said mechanism against releasing movement, and a switch controlled by the position of said fuse assembly for establishing connection through said second cut-out upon blowing of said first cut-out.
16. A repeating electrical construction comprising a first cut-out and a second cut-out, said first cut-out comprising a housing having contacts, a door for said housing, said door and housing providing a downwardly flaring opening in the lower portion of said structure, a fuse assembly having spaced contacts normally engaging the contacts of said housing, mechanism releasably holding said fuse assembly in position, a fuse link forming a portion of said fuse assembly and normally holding said mechanism against releasing movement, a switch controlled by the position of said fuse assembly for establishing connection through said second cut-out upon blowing of said first cut-out.

connection through said second cut-out upon blowing of said first cut-out, and time delay mechanism for delaying the operation of said switch.

- 5 17. A repeating electrical construction comprising a first cut-out and a second cut-out, said first cut-out comprising a housing having contacts, a door for said housing, said door having a portion spaced outwardly from said housing, a fuse tube having spaced contacts normally engaging the contacts of said housing and having a fuse link electrically joining the contacts of said fuse tube, means for guiding said fuse tube for opening the electric circuit through 10 said first cut-out by the mechanical motion of said fuse tube from operative to inoperative position, restraining means controlled by said fuse link for normally holding the fuse tube in place, and a normally open switch biased towards closed 15 position for establishing connection through said second cut-out upon the blowing of said first cut-out, said fuse tube moving towards said spaced portion of said door when said fuse tube moves towards inoperative position.
- 20 18. A cut-out comprising a casing having spaced contacts and having a door, a fuse tube located within said casing and having contacts normally engaging said spaced contacts, said fuse tube and said door constituting a fuse tube assembly, a fuse link carried by said fuse tube and normally electrically joining the contacts of said fuse tube, said cut-out having a third contact normally insulated from said first mentioned spaced contacts, a lever normally supporting said fuse tube assembly with the fuse tube in operative position and being restrained against releasing motion by said fuse link, whereby when said fuse link blows, said fuse tube assembly will move away from said spaced contacts, and 25 40 switch means movable to closed position when said fuse blows and establishing electrical connection between one of said spaced contacts and said third contact.
- 25 19. A cut-out comprising a casing having spaced contacts and having a door, a fuse tube located within said casing and having contacts normally engaging said spaced contacts, said fuse tube and said door constituting a fuse tube assembly, a fuse link carried by said fuse tube and normally electrically joining the contacts of said fuse tube, said cut-out having a third contact normally insulated from said first mentioned spaced contacts, a lever normally supporting said fuse tube assembly with the fuse tube in operative position and being restrained against releasing motion by said fuse link, whereby when said fuse link blows, said fuse tube assembly will move away from said spaced contacts, switch means biased towards closed position and normally restrained by said fuse tube and movable to closed position when said fuse blows and establishing electrical connection between one of said spaced contacts and said third contact, and time delay mechanism for delaying the closing motion of 30 35 said switch means.
